United States Patent Office

Des. 181,328
Patented Oct. 29, 1957

181,328

DINNER PLATE OR SIMILAR ARTICLE

Michael Joseph Szymanski, Camillus, N. Y., assignor to Onondaga Pottery Company, Syracuse, N. Y., a corporation of New York

Application March 11, 1957, Serial No. 45,190

Term of patent 14 years

(Cl. D44—15)

The drawing is a plan view of a plate of conventional configuration, showing my new design.

I claim:

The ornamental design for a dinner plate or similar article, as shown and described.
